BOOKSTAND

Filed April 10, 1929

UNITED STATES PATENT OFFICE

RUFUS WAPLES, OF PHILADELPHIA, PENNSYLVANIA

BOOKSTAND

Application filed April 10, 1929. Serial No. 353,987.

This invention relates to a bookstand, and is more particularly concerned with the design and construction of a bookstand whereby the book is adequately and positively braced, and may be pulled towards or away from the reader at will.

An object of the invention is to devise a new and improved rotatable bookstand.

Another object is to produce a new and improved bracing for a bookstand.

Another object is to produce a new form of page clamp for a bookstand.

Another object is to produce a new form of rotatable rod together with means for inserting and holding said rod, the said rod containing the page clamping elements of a bookstand.

Another object is to produce in a bookstand having a base member and a hook holding member, a new and improved form of clamping means for securing the book holding member to a cooperating arm.

Still another object is to produce a new form of union between the telescoping arms of a bookstand whereby one of the arms has limited angular movement with respect to the other.

Other objects will appear hereinafter.

In the drawing, in which is illustrated one form of my invention:

Fig. 1 is a perspective illustrating my invention in operative relation with a chair or similar article;

Fig. 2 is a section through the lower portion of the book holder platform illustrated in Fig. 1;

Fig. 3 is a sectional view illustrating the book holding arm operatively associated with the clamping member;

Fig. 4 is a detail of the page clamping actuating means parts being shown in dotted outline for the sake of clarity;

Fig. 5 is a detail of the head of the upstanding arm on the base member;

Fig. 6 is a perspective detail of the clamping member of Figs. 1 and 3, while

Fig. 7 is a detail on a reduced scale of the clamp member of Fig. 2.

At 1 is broadly indicated the base member of the stand comprising elongated feet 2 and

3 and shorter feet 4 and 5, joined together by suitable means such as a union 6, to one side of which is secured a tubular arm 7 adapted to telescopically receive a book-holding arm 8. The arm 7, as perhaps better illustrated in Fig. 5, is provided at its extremity remote from the union 6 with a peripheral recess 9 preferably extending for approximately 90° around the circumference thereof. This recess is adapted to receive and cooperate with a pin 10 formed on the underside of a clamp member 11, shown in the present form as having a circularly located aperture 12, a portion 13 of the circumference of which is preferably flattened or distorted in other suitable manner from a true circle, and which is apertured on its circumference for the reception of a set-screw or the like 14 which preferably has a head 15. The clamp member 11 is fitted about the book holding arm 8 which in the present instance is provided along the greater portion of its extent with a flattened or other suitably shaped surface 16 adapted to cooperate and interlock with the portion 13 of the clamp member, thus permitting a unitary rotational movement of the arm and clamp member but permitting relative longitudinal movement of the arm with respect to the clamp.

When the arm 8 is properly located in its vertical position with respect to the arm 7, the head of the set-screw 14 is rotated to fit the clamp member to the arm 8. The pin 10, fitting into the recess 9 then permits relative rotational movement of the arm 8 with respect to the arm 7, the trajectory being determined by the abutment walls 17 and 18 formed by the recess 9.

It will be noted in connection with the base member that the elongated arms 2 and 3 are preferably adjacent each other and in the present instance define an arc therebetween of approximately 90°. These arms extend outwardly to a sufficiently great distance to underlie a book-holding platform, broadly indicated by the reference numeral 19. The recess 9 in the arm 7 is preferably so constructed that the abutments 18 and 17, respectively, overlie the feet 2 and 3, thus limiting the trajectory of the book platform

19 within the boundaries defined by the elongated feet.

In operation, one foot 3 is placed underneath the chair or similar device 20', while 5 the other extends outwardly from the side thereof. When the reader is using a heavy book for a reference, he may pull the platform 19 and arm 8 towards him into a reading position; while when he desires to jot 10 down notes or has some other reason to push the book away into a position substantially overlying the foot, it is necessary only to push the book away, to the side. It will be noted that in any position of the platform with its 15 book, it is adequately braced by the feet 2 and 3.

The platform, as illustrated in Fig. 1, in the preferred form consists of a plurality of transverse members 20 joined at their outer 20 ends by cross members 21 and 22, preferably of L-section. An additional brace is illustrated as comprising the broad, centrally located transverse member 23. An important feature of my invention is resident in the 25 page-clamping members and apparatus for actuating them. The L-member 22 is arranged with its outermost flange extending outwardly from the platform 19. Fixed to the outer side of this flange, hollow end caps 30 24 and 25 are shown as extending longitudinally of the platform and having cooperating openings at their inner ends. Within the cap 24 a resilient means is mounted, in the present instance comprising a coiled spring 35 26 affixed at one end to a pin 27 affixed to the cap, or to other suitable means. This spring is adapted to yieldingly urge a rod 28 or the like outwardly from the cap 24 so that a suitably recessed head 29 at the opposite end of the rod will be urged into cooperative relationship with a cotter pin 30, or the like, removably inserted transversely of the cap 25 adjacent to one end thereof. As shown, the cap 25 is open at both ends.

40 When first inserting a rod into the caps, the pin 30 is removed and the rod is inserted from the outer end of the cap 25 into the open end of the cap 24, compressing the spring 26. Having backed the rod a sufficient 45 distance in the cap 24 so that the recessed head 29 will clear the openings for the pin 30, the pin is reinserted and the rod, when released, will be urged into interlocking engagement therewith. Fitted into the rod 28, 50 which may be of wood or other suitable material, are page-clamps 31 and 32, having inturned portions 33 and 34, respectively, which may, by rotation of the rod 28, be moved into or out of clamping relation with 55 a book held on the platform 19. When turning the pages of a book, it is necessary only to move the rod 28 to the left to clear the pin 30 and to then rotate it outwardly so that the clamps will assume the position indicated in dotted outline in Fig. 2. The pages

60 may then be turned, after which the reverse operation is employed to restore the clamp members to their operative position. It is understood that any other clamping means 65 may be employed without departing from the spirit of my invention.

70 The rod 8 is shown as having a transversely or horizontally extending portion 35 to which the platform 19 may be adjustably secured in any suitable manner. As shown, the clamp member 36 is adjustably secured to the rear of the platform 19, preferably along the central transverse member 23. A headed bolt 75 37 extends rearwardly from the member 23 and adjustably secures one extremity of the clamp member 36, while another headed bolt 80 38 performs a similar function at the opposite end thereof. Suitable recesses 39 and 40 are provided in the clamp member 36 and transverse member 23, respectively, to adapt 85 the same to the contours of the arm 35. Means such as a headed bolt 41 extends through the clamp member 36, into operative relation with the arm 35, to clamp the member thereto. By simultaneously adjusting the bolts 38 and 41, the bolt 37 being left in a fixed position, it is possible to tighten the clamp platform 19 to the arm 35. By this mechanism, the platform may be placed in any desirable angular relation with respect 90 to its supporting arm and to the reader. It is apparent of course, that this construction may be varied at will without departing from the scope of the invention.

95 It is of course understood that the invention is susceptible to numerous modifications and adaptations, and it is intended that it be limited only by the scope of the appended claims.

100 I claim:

105 1. In a bookstand, a book-holding arm, having a laterally extending portion; a book-holding platform cooperable therewith, a clamping bar extending transversely of said platform for at least a portion of its extent, means adjacent each end of said clamping bar for adjustably securing it to said platform, and means adjacent one end of said bar for adjustably securing it to said laterally extending portion.

110 2. In a bookstand, a book-holding arm, at least a portion of which extends in a substantially lateral direction, a book-holding platform adaptable for adjustable reception about the lateral portion of said arm, a clamp member extending transversely along the rear of said platform for at least a portion of its extent, bolts adjacent each extremity of said clamping member for adjustably securing it to said platform, and an additional bolt for adjustably securing the clamping member to the arm.

115 3. In a bookstand, a book-holding arm, at least a portion of which extends laterally, a book-holding platform adjustably mounted

on the lateral portion of said arm, a clamp member extending transversely along the rear of said platform for at least a portion of its extent, and having recesses adapted to the contour of said arm, a bolt adjacent one end of said clamp member for securing it to said platform, another bolt adjacent the other end of said clamp member for adjusting the same relative to the platform, and means adjustably clamping said member to the arm and cooperable with said second-mentioned bolt to hold the platform in a predetermined position.

4. In a support, a platform, a supporting standard therefor, and a base member from which the standard arises, said base member including feet radiating from the lower end of the standard, said feet being arranged in groups, the feet of each group being of equal length, the feet of different groups being of different lengths, there being two feet in the group having the greater length, said feet being spaced through approximately 90 degrees, said standard being formed in two sections of which the upper section has an angular extension supporting the platform, the sections of the standard being capable of relative rotation and means operatively connecting said standard sections and limiting relative rotation of the sections to an angle, throughout which said angular arm and the platform are maintained within the angle defined by the longer feet.

5. In a support, a platform, a supporting standard therefor, a base member from which the standard arises, said base member including feet radiating from the lower end of the standard, said feet being arranged in groups, the feet of each group being of equal length, the feet of different groups being of different lengths, there being two feet in the group having the greater length, said feet being spaced through approximately 90 degrees, the sections of the standard being telescopically engaged and the upper section thereof having an angular extension, and a member having splined engagement with one of said sections and a pin-and-notch engagement with the other of said sections and being vertically adjustable upon the first-named section, the pin-and-notch connection of said member with the last-named section limiting movement of the angular extension to a sector vertically overlying the angle defined by the longer feet.

6. In a support, a platform, a supporting standard therefor and a base member from which the standard arises, said base member including feet radiating from the lower end of the standard, there being two adjacent feet having greater length than the remainder thereof, said feet being spaced through approximately ninety degrees, said standard being formed in two sections of which one comprises an angular extension supporting

the platform and is rotatable with relation to the other section, and means operatively connecting the sections and limiting rotation of the first-named section to maintain said angular extension in positions within the angle defined by the longer feet. 70

7. In a support, a platform, a supporting standard therefor and a base member from which the standard arises, said base member including feet radiating from the lower end of the standard, there being two adjacent feet having greater length than the remainder thereof, said feet being spaced through approximately ninety degrees, said standard being formed in two sections of which the upper 80 has an angular extension supporting the platform and is rotatable with relation to the lower section, and a member having splined engagement with one of said sections and a pin and notch engagement with the other of said sections and being vertically adjustable upon the section having the angular extension, the pin and notch connection of said member with the other section limiting movement of the angular extension to a sector vertically overlying the angle defined by the longer feet. 85 90
